UNITED STATES PATENT OFFICE.

JOHN H. ROSS, OF KANSAS CITY, MISSOURI.

MOLD FOR CASTING VENT-PIPE FLASHINGS.

1,296,321.

Specification of Letters Patent. Patented Mar. 4, 1919

Application filed November 4, 1918. Serial No. 260,997.

To all whom it may concern:

Be it known that I, JOHN H. ROSS, a citizen of the United States, residing at Kansas City, in the county of Jackson and State of Missouri, have invented certain new and useful Improvements in Molds for Casting Vent-Pipe Flashings, of which the following is a specification.

My invention relates to a mold for casting vent pipe flashings in one piece, and my object is to provide a mold of this character wherein vent pipe flashings may be produced more quickly and economically than heretofore.

Heretofore, it has been customary to form the tube and the flat sheet of vent pipe flashings separately and then solder or otherwise secure them together. Such procedure is expensive as it involves considerable time and labor and the product is not of uniform quality owing to defective or leaky joints being formed between the tubes and the flat sheets.

By the use of my mold the product is cast in one piece, preferably of lead, and comes out of the mold ready for use, thereby saving the time and expense required in placing the old two-piece product together.

In order that the invention may be fully understood, reference will now be made to the accompanying drawings, in which:

Figure 1 is a front elevation partly broken away of the mold in locked position.

Fig. 2 is a broken side elevation of the mold in locked position.

Fig. 3 is a vertical section on line III—III of Fig. 1.

Fig. 4 is a transverse section on line IV—IV of Fig. 1, with some of the parts removed.

Fig. 5 is a detail perspective of a core forming a part of the mold.

Fig. 6 is a broken detail perspective of a shaft and eccentrics associated therewith.

In carrying out the invention, I employ two main members 1 and 2 reinforced by marginal flanges 4 and 5, and short intermediate flanges 3 and 6, respectively. The main member 2 is also provided at its inner face with bottom and side flanges 7, which constitute the boundary for three sides of a sheet-like space 9 between the adjacent faces of the members 1 and 2. A gate 11 at the upper ends of the main members 1 and 2, communicates with the space 9, so that the molten metal may be poured therein. Said

gate 11 is provided with a spreader 10 to direct the molten metal around opposite sides of a tubular core 26, hereinafter referred to.

The main members 1 and 2 are provided with ears 13 and 14, respectively, at their lower ends to receive a pivot 16, so that said members 1 and 2 may be opened and closed. The opening movement of the members is limited by stops 18, which project from the ears 13 into the path of the lower transverse flange 5 on the main member 2.

Feet 20 extend down from the ears 14 to provide a support for the mold when the same is raised to vertical position to receive the molten metal. The pivot 16 may also act as a support for the mold and with that end in view it is extended longitudinally beyond the ears 14, as disclosed on Figs. 1 and 4, a suitable frame, not shown, being provided to support the pivot 16 and the main member 1 when the mold is in use.

22 designates a tubular protuberance extending backwardly and downwardly from the main member 1 and provided at its rear margin with an internal annular flange 24. As disclosed by Fig. 3, said tubular protuberance 22 extends downwardly at an angle of about forty-five degrees from the member 1 to give the proper pitch to the tubular portion of the product cast in the mold.

26 designates the tubular core which is adapted to extend through the tubular protuberance 22 and have its rear end fit snugly within the annular flange 24, so that the molten metal poured into the mold can not escape between said flange 24 and the core 26. The front end of the core 26 is provided with an external marginal flange 30, adapted to fit snugly within an opening 31 in the main member 2. As disclosed by Fig. 3, the tubular protuberance 22, the core 26 and its flange 30 taper downwardly. This construction permits the core 26 and its flange 30 to engage the flange 24 and the surrounding wall of the opening 31, respectively, and thus limit the inward movement of the core 26. It also permits the core 26 to be readily released from the tubular portion of the casting and gives sufficient taper to said tubular portion to permit it to be readily withdrawn from the tubular space 33, between the interior of the tubular protuberance 22 and the exterior of the core 26. 35 designates a hand lever fixedly-mounted upon a shaft 36 rockably-mounted in oppo-

sitely-disposed bearings 37 on the core flange 30. Said shaft 36 is provided at its ends with fixedly-mounted eccentrics 39, carrying laterally extending eccentrically-mounted pins 40 operably-arranged in the slotted portions 41 of lugs 42, fixed to the longitudinal flanges 5 of the main member 2.

45 designates a hand crank fixedly-mounted upon a shaft 47 journaled in oppositely-disposed bearings 48 at the upper portion of the main member 2. The shaft 47 is provided at its ends with fixedly-mounted eccentrics 50, having eccentric pins 51 adapted to engage keepers 52 fixed to opposite sides 15 of the main member 1.

53 designates a link pivotally-connected at its ends to the hand crank 45 and a crank 54, which latter is fixed upon a shaft 55 rockably-mounted in oppositely-disposed bearings 57 fixed to the lower portion of the main member 2. Said shaft 55 is provided at its terminals with fixedly-mounted eccentrics 59, having eccentric pins 60 adapted to engage keepers 62 fixed to opposite sides 25 of the main member 1.

63 and 64 designate handles at the upper portions of the main members 1 and 2, respectively, whereby the same may be opened and closed.

80 In practice, the mold is supported in upright position and the main members 1 and 2 are firmly locked together in closed position by swinging the hand crank 45 downwardly to the position disclosed by Fig. 3. As the 35 hand crank 45 is swung downwardly, it, through the intermediacy of the intervening parts, rocks the eccentric pins 51 and 60 into engagement with the hook-shaped terminals 65 and 66 of the keepers 52 and 62, 40 respectively, and forces the flanges 7 of the main member 2 tightly against the inner face of the main member 1. The core 26 is then forced inwardly until its rear terminal and flange 30 are firmly seated in the flange 24, 45 and the wall of the surrounding opening 31, respectively, in the main member 2. This is accomplished by raising the lever 35 to the position disclosed by Fig. 3. As the lever 35 moves upwardly, it through the intermediacy of the intervening parts, forces the 50 eccentric pins 40 against the edges 70 of the slots 41, and forces the shaft 36 and the bearings 37 toward the main member 1 and thus firmly seats the core 26, as above described. As the core 26 moves inwardly its flange 31 is guided by the beveled ends 6^a of the short flanges 6, so that it will be properly seated. The metal is then poured into the gate 11, where it is divided by the 60 spreader 10, which causes it to flow down at opposite sides of the core 26 and fill the lower portion of the space 9 before the tubular space 33 and the upper portion of said space 9 are filled with metal. Thus a good 65 casting free from blow-holes is assured.

After the metal in the mold cools sufficiently, the core 26 is released from the tapered tubular portion of the casting by swinging the hand lever 35 downwardly, and through the intermediacy of the intervening parts, 70 cause the eccentric pins 40 to bear against the edges 72 of the lugs 42, whereby sufficient leverage is afforded to readily release the core 26 from the casting as above described. The main member 2 is then unlocked from the main member 1 by swinging the hand crank 45 upwardly, which, through the intermediacy of the intervening parts, causes the eccentric pins 51 to rock into engagement with the edges 74 of the 80 keepers 52, whereby sufficient leverage is obtained to pry the member 2 away from the member 1 and the casting. This operation also rocks the eccentric pins 60 out of engagement with the keepers 62, so that the 85 lower portion of the member 2 is free to swing open. The handles 63 and 64 are then grasped and the main member 2 is swung open far enough to permit ready removal of the casting from the member 1. 90

From the foregoing description, it is apparent that I have produced a mold wherein vent pipe flashings can be quickly cast in one piece, and while I have shown and described the preferred form of my invention, I reserve the right to make such changes in the construction, combination, and arrangement of parts as properly fall within the spirit and scope of the claims.

Having thus described my invention, what 100 I claim and desire to secure by Letters Patent, is:

1. In a mold of the character described, two main members adapted to fit together and having a sheet-like space between them, 105 a gate leading from the exterior of said members to the said space, a tubular protuberance projecting from one of the main members, and a core operably-mounted on the other main member and adapted to extend into the tubular protuberance, a tubular space being formed between the protuberance and said core and communicating with the sheet-like space between the two main members. 110

2. In a mold of the character described, two main members adapted to fit together and having a sheet-like space between them, hinge-like means operably-connecting said members together, a gate leading from the exterior of said members to the said space, a tubular protuberance projecting from one of the main members, and a core operably-mounted on the other main member and adapted to extend into the tubular protuberance, a tubular space being formed between the protuberance and said core and communicating with the sheet-like space between the two main members. 120

3. In a mold of the character described, 130

- two main members adapted to fit together and having a sheet-like space between them, hinge-like means operably-connecting said members together so that they may be opened and closed, a gate leading from the exterior of said members to the said space, a spreader in said gate, a tubular protuberance projecting from one of the main members, and a core operably-mounted on the other main member and adapted to extend into the tubular protuberance, a tubular space being formed between the protuberance and said core and communicating with the sheet-like space between the two main members.
- 5 4. In a mold of the character described, two main members adapted to fit together and having a sheet-like space between them, means on said main members whereby they may be locked together and forced apart, hinge-like means operably-connecting said members together so that they may be opened and closed, a gate leading from the exterior of said members to the said space, a spreader in said gate, a tubular protuberance projecting from one of the main members, and a core operably-mounted on the other main member and adapted to extend into the tubular protuberance, a tubular space being formed between the protuberance and said core and communicating with the sheet-like space between the two main members.
- 10 5. In a mold of the character described, two main members adapted to fit together and having a sheet-like space between them, a gate leading from the exterior of said members to the said space, a tubular protuberance projecting from one of the main members, a core operably-mounted on the other main member and adapted to extend into the tubular protuberance and said core communicating with the sheet-like space between the two main members, eccentric means for adjusting the core longitudinally of the tubular protuberance.
- 15 6. In a mold of the character described, two main members adapted to fit together and having a sheet-like space between them, a gate leading from the exterior of said members to the said space, a tubular protuberance projecting from one of the main members, a core operably-mounted on the other main member and adapted to extend into the tubular protuberance and said core communicating with the sheet-like space between the two main members, eccentric means fixed to said shaft, means on the adjacent main member and engaging said eccentric means, and means for rocking the shaft to effect longitudinal adjustment of the core relative to the tubular protuberance through the intermediacy of said eccentric means and the engaging means.
- 20 7. In a mold of the character described, two main members adapted to fit together and having a sheet-like space between them, a gate leading from the exterior of said members to the said space, a tubular protuberance projecting from one of the main members, a core operably-mounted on the other main member and adapted to extend into the tubular protuberance, a tubular space being formed between the protuberance and said core and communicating with the sheet-like space between the two main members, a shaft journaled at one end of the core, eccentric means fixed to said shaft, means on the adjacent main member and engaging said eccentric means, and means for rocking the shaft to effect longitudinal adjustment of the core relative to the tubular protuberance through the intermediacy of said eccentric means and the engaging means.
- 25 8. In a mold of the character described, two main members adapted to fit together and having a sheet-like space between them, a gate leading from the exterior of said members to the said space, a tubular protuberance projecting from one of the main members, a core operably-mounted on the other main member and adapted to extend into the tubular protuberance, a tubular space being formed between the protuberance and said core and communicating with the sheet-like space between the two main members, a shaft journaled on one of the main members, eccentric means on said shaft, means on the opposing main member adapted to be engaged by said eccentric means, and means for rocking the shaft to lock and unlock the two main members through the intermediacy of the eccentric means and the means adapted to be engaged thereby.
- 30 9. In a mold of the character described, two main members adapted to fit together and having a sheet-like space between them, a gate leading from the exterior of said members to the said space, a tubular protuberance projecting from one of the main members, a core operably-mounted on the other main member and adapted to extend into the tubular protuberance, a tubular space being formed between the protuberance and said core and communicating with the sheet-like space between the two main members, shafts journaled on one of the main members, eccentric means on said shafts, means on the opposing main member adapted to be engaged by said eccentric means, cranks fixed to said shafts to rock the same and lock and unlock the two main members through the intermediacy of the eccentric means and the means adapted to be engaged thereby, and a link connecting said cranks to cause them to operate in unison.
- 35 10. In a mold of the character described, two main members adapted to fit together and having a sheet-like space between them,

a gate leading from the exterior of said members to the said space, a tapered tubular protuberance projecting from one of the main members and provided at its reduced 5 end with an internal flange, a tapered core operably-mounted on the other main member and adapted to extend into the tubular protuberance and have its reduced terminal fit snugly within said internal flange, a tubular 10 space being formed between the protuberance and said core and communicating with the sheet-like space between the two main members, and a tapered flange at the large 15 terminal of the core adapted to fit snugly within a corresponding opening in the adjacent main member.

11. In a mold of the character described, two main members, marginal flanges on the

face of one member and adapted to abut the face of the companion member and leave a sheet-like space between said faces, a gate 20 leading from the exterior of said members to the said space, a tubular protuberance projecting from one of the main members, and a core operably-mounted on the other 25 main member and adapted to extend into the tubular protuberance, a tubular space being formed between the protuberance and said core and communicating with the sheet-like space between the two main members. 30
